UNITED STATES PATENT OFFICE.

GEORGE VINING, OF HARTFORD, CONNECTICUT.

VALVE.

SPECIFICATION forming part of Letters Patent No. 429,294, dated June 3, 1890.

Application filed December 7, 1889. Serial No. 332,915. (No model.)

To all whom it may concern:

Be it known that I, GEORGE VINING, of Hartford, in the county of Hartford and State of Connecticut, have invented certain new

5 and useful Improvements in Valves, of which the following is a full, clear, and exact description, whereby any one skilled in the art can make and use the same.

10 The object of my invention is to provide a fluid-valve that shall be simple and strong in construction, and provided with means for compensating automatically for any wear of the plug or gates, so that a leaking of the valve is practically prevented.

15 To this end my invention consists in the combination, with the sectional valve-body having the fluidway, of the valve-gates and gate-supports, with the chamber between them and the valve-spindle; and it further 20 consists in details of the severals parts, and in their combination, as more particularly hereinafter described, and pointed out in the claim.

25 Referring to the drawings, Figure 1 is a detail view, in vertical central section, through the valve body and gates on a plane in line with the axis of the valve inlet and outlet. Fig. 2 is a detail view, in cross-section, of the valve-body at right angles to the line of the 30 openings. Fig. 3 is a detail view, in horizontal section, through the valve on plane denoted by line $x y$ of Fig. 1.

35 In the accompanying drawings, the letter a denotes a valve-body that may be made in the usual manner and of metal cast to shape; b , the inlet, and c the outlet formed for the passage of the fluid through the walls of the valve-body. The upper part of the valve-body is closed by means of a screw-cap d , having an opening for the passage of the valve-spindle e , the said opening being packed by a gland f of the usual construction.

40 Within the valve-body the gates g g' are arranged in a vertical position, with their outer faces shaped to snugly fit the inner wall of the valve-body, the gates extending from top to bottom of the chamber in the valve-body, and being of a width to extend completely across the inlet and outlet openings in the valve-body. These gates are preferably made separate from the valve-spindle and provided with tongues or projections h ,

that fit into grooves h' in the lower end of the valve-spindle in such manner as to cause the gates to slide (in this case in a circular plane) 55 whenever the valve-spindle is rotated.

It is important to the operation of my improvement that there shall be a chamber i beneath the valve-spindle and between the gates in line with the inlet and outlet openings of 60 the valve-body. The function or purpose served by this chamber is to receive any fluid that may leak through from the inlet side b of the valve, so that whatever pressure there may be on the inlet side of the valve shall be utilized to pack the valve in case there is any leakage of the fluid into this chamber by reason of the wear of the parts that are sliding in contact.

65 In addition to the separate gates g g' , the lower end of the piston is provided with spring-chambers, in which are seated springs j , that thrust outward against the back faces of the gates about central of their length and tend to pack the valve by holding the gates 75 in close contact with the inner walls of the valve.

70 In order to prevent the springing of the lower end of the gates by reason of any great pressure that may be brought upon them, the lower ends are supported by the disk k , that may be inserted between them; or the lower ends of the gates may enter an annular groove 75 cut into the bottom of the valve-body.

I claim as my invention—

85 In a valve, in combination with the valve-body having the inlet and outlet openings, the gates extending from top to bottom within the valve-chamber and adapted to cover the respective openings through the valve-body, 90 the spindle engaging lugs on the inner sides of the gates, the spindle with the lug-sockets and the spring-sockets, the springs seated in radial sockets in the valve-spindle, the chamber below the bottom end of the valve-spindle, and between the back surface of the gates in line of the openings through the valve-body and the gate-supporting groove in the bottom of the valve-body, all substantially as described.

GEORGE VINING.
